STAPLE AND HASP CONSTRUCTION

Filed Nov. 6, 1926

Inventor:

Daniel Nelson

By Willement, Audley, Byron & Knight
London

UNITED STATES PATENT OFFICE

DANIEL NELSON, OF OAK PARK, ILLINOIS, ASSIGNOR TO MARSHALL FIELD & COMPANY, OF CHICAGO, ILLINOIS, A CORPORATION OF ILLINOIS

STAPLE AND HASP CONSTRUCTION

Application filed November 6, 1926. Serial No. 146,588.

The subject matter of the present application relates to an improved hasp and staple structure for use in securing doors or other closures.

5 The forms of my invention disclosed in Figures 1 to 5 inclusive and the description therefor which constitutes part of the subject matter of this application, will be found in my earlier application, Serial No. 20,926, filed April 6, 1925.

One of the objects of my invention is to provide a hasp and staple structure which will not be subject to accidental release.

Another object of my invention is to provide a staple having a notched resiliently mounted leg adapted to engage a hasp in a manner to hold it against accidental release but which may be forced to release position.

20 Another object of the invention is to construct a staple together with its attaching base from a single piece of plate metal, to which end one feature of the invention consists in punching a piece of plate metal in a manner to displace therefrom a tongue of metal of suitable dimensions to form by looping the tongue the staple to be produced, one end of the tongue being left integral with the plate and in upstanding relation thereto, and the other end of the tongue being provided by the form of the punching die with a cross-head of a dimension suitable to adapt the crosshead to engage beneath the plate from which the tongue is punched, and thereby serve as a means for anchoring the free end of the tongue to the attaching plate.

25 In the preferred embodiment of this part of the invention, the crosshead bridges the slot left by punching out the tongue, and the plate is perforated on either side of said slot in a manner to permit the ends of the crosshead to be passed through the apertures and clinched beneath the plate as a means for anchoring the free end of the tongue to the plate.

30 A further object of my invention is to provide an improved hasp for use with staples embodying the above described features in which a means is provided for causing the movable leg of said staple to disengage said hasp upon manipulation of the device in a

manner to remove the hasp from said staple.

It is to be understood in connection with this invention that the improved hasp may be used with any one of the disclosed forms of staples, it only being necessary to select 55 one which has a movable leg provided with a hasp engaging notch, or the staple may be used with a hasp of ordinary structure, the disengagement in such a case being accomplished by forcing the hasp in an outward 60 direction.

Another object of the invention is to provide a staple that will be resilient under the engagement of the hasp or the keeper with which it is to be used, and to this purpose, 65 the staple has inherent resiliency and the free end of the staple is movable on the plate to which it is anchored, preferably in a plane which includes the two legs of the staple so that when the staple is so locked that the keeper impinges against the movable leg of the staple, it will bind in such position and be secure against unintentional displacement, and in the preferred embodiment of this part 70 of the invention, the movable leg of the staple is provided with a recess or undercut in which the keeper engages, or through which to provide an overhang and render the keeper 75 more secure against unintentional displacement. 80

The feature of having one leg of the staple resilient or movable and provided with a recess in order that the keeper may interengage therewith, is not limited in its application to a staple struck up from plate metal and having its movable leg anchored through means of a crosshead but may be embodied in a staple constructed with a looped rod or wire having its ends riveted in the base plate. 85

These and other objects are accomplished 90 by means of the arrangement disclosed on the accompanying sheet of drawings, in which—

Figure 1 shows a perspective view of a staple and hasp made in accordance with my 95 invention;

Figure 2 shows a cross sectional view of Figure 1 disclosing the manner in which the hasp fits the notched staple and the resilient leg yieldingly held in the base plate;

Figure 3 is a showing of a modified form of 100

staple structure produced from plate metal;

Figure 4 is a cross sectional view of the structure shown in Figure 3 taken on the line 4^x—4^x;

5 Figure 5 is a cross sectional view of Figure 4 taken on the line 5^x—5^x; and

Fig. 6 is a showing of a modified form of hasp which has a releasing device but which may be used with any of the various types 10 of staple structures.

10 Figure 7 is a perspective view of the staple shown in Figure 3, with a modified form of hasp.

15 The various novel features of the invention will be apparent from the following description and drawings and will be particularly pointed out in the appended claims.

20 Referring to the drawings, it will be noted that my invention embraces an improved staple structure and a hasp therefor, modified forms of the staple being shown in Figures 2 and 3, either of which may be used with the type of hasp shown in Figure 1 or the type shown in Figure 6, the latter being 25 provided with a staple engaging lever.

Referring to Figures 1 and 2, the type of staple shown embodies an attaching plate 10 and a U-shaped portion 11, one end of which is rigidly attached as at 12 to the plate 10 30 by riveting or any other suitable means, the opposite end being inserted as at 13 in an opening in the plate 10 in a manner to permit a slight movement. Closely adjacent the plate, the staple 11 is provided with a notch 35 14 adapted to receive the hasp, the relationship of these parts being such that when the hasp and staple are in co-operating position, as shown in Figures 1 and 2, the hasp is maintained against accidental displacement by the 40 notch 14. As shown in these figures, the hasp comprises an attaching plate 15 and a hinge portion 16 provided with a slot 17 adapted to receive the staple 11, the plate 16 being pivoted to the attaching plate as at 18.

45 Referring to Figures 3, 4 and 5, 20 represents an attaching base, 21 the staple member of a staple for hasps or other keepers for doors or other closures, both of which members are formed from a single blank of plate

50 metal, by subjecting the blank to punching dies shaped to strike from the plate a tongue having the dimensions of the staple member 21 and severed therefrom on all sides except at one end where it is left integral with the plate. The tongue or staple member 21 carries a crosshead 22 of sufficient dimensions to adapt it to bridge the slot 23 left in the plate 20 and also of sufficient dimension to provide clinching ends 24 which are inserted through

55 apertures 25 also punched in the plate 20 and clinched beneath said plate in a manner to provide a firm anchorage for the free end 26 of the tongue in completing the staple. Preferably the apertures 25 which receive the 60 crosshead 22 of the staple member are elongated in a plane parallel to that of the staple so that the anchored end may move slightly relatively to the integral unit or immovably mounted end 27 of the staple member and this condition, coupled with the condition of inherent resiliency in the staple member, adapts the staple to yield to impingement of the end of the slot 28 formed in the hasp 29 when the staple and hasp are mounted in 70 properly selected positions, and thus cause the hasp to bind in its engagement with the staple and be secure against unintentional displacement. In order to afford greater security in this binding of the hasp upon the staple, the movably anchored end or leg of the 75 staple may be formed with the recess 30, which provides a shoulder or overhang to engage the hasp as the movable leg springs back into position.

Referring to Figure 6, the type of hasp 80 there disclosed comprises an attaching plate 31 hinged as at 32 to a staple engaging portions 33, this last named portion having a suitable slot 34 adapted to receive the U-shaped portion of the cooperating staple in the manner shown. The staple in this figure comprises a U-shaped portion 35 and an attaching plate 36 having screw holes 37, it being understood, however, that the type of hasp shown in this figure may be used with the 85 type of staple shown in either Figure 2 or Figure 3, it only being necessary to provide a staple with one notched movable leg. The outer end of the hasp portion 33 is provided with upstanding ears 38 apertured as at 39 to form bearings for the pivoted lever 40 having integral pivoted projections 41. The lever 40 is provided with a staple engaging portion 42 and an outer end constructed to be 90 easily engaged or manipulated by the same movement necessary to remove the hasp from the staple. The length of the lever plate 40 is so selected relative to the cooperating staple that the lever will normally engage the staple at the upper portion thereof but which 95 will effect through a camming action the movement of the movable leg to an extent sufficient to release the hasp from the notch.

Referring now to Figure 7, the same type of hasp as shown and described in connection with Figure 6 is shown as applied to the form of staple disclosed in Figure 3. The operation will be exactly the same, and inasmuch as the various parts are designated by the same reference characters, further description is believed to be unnecessary.

To operate this type of hasp, it is merely necessary to engage the under side of the outer end of the lever 40 and lift upwardly, the first movement causing the staple leg to disengage the hasp and the continued movement causing the hasp to be removed therefrom. The operation of the type of hasp shown in Figures 1 and 2 is simply that of a camming action of the rounded edge of the 125 130

openings against the edge of the hasp, this movement being effected by forcing the hasp out of engagement in a direction away from the staple plate.

5 I claim:

1. Latching means for hasps comprising an attaching base, and an inherently resilient staple constructed with one leg fixedly mounted on said base and its other leg movably anchored to the base and having a limited movement relative to the fixed leg, said movably anchored leg having a recess adapted to engage a hasp and adapted to pass an inter-engaging portion of said hasp to and from its recess by the resilient action of the staple.
2. A staple for hasps, comprising an attaching plate and a staple carried by said attaching plate, with one leg resilient, said staple comprising a tongue of metal stamped from the attaching plate and formed into a loop and having a cross-head which bridges the slot in the plate left by said tongue.
3. A staple for hasps, comprising an attaching plate and a staple carried by said attaching plate, with one leg resilient, said staple comprising a tongue of metal stamped from the attaching plate and formed into a loop and having a cross-head which bridges the slot in the plate left by said tongue, said crosshead being secured against lifting from the base plate.
4. A staple for hasps, comprising an attaching plate and a staple carried by said attaching plate, with one leg resilient, said staple comprising a tongue of metal stamped from the attaching plate and formed into a loop and having a cross-head which bridges the slot in the plate left by said tongue, said crosshead having its ends clinched on the underside of the plate, on either side of the slot thereby securing said crosshead against lifting from the plate.
5. A staple for hasps, comprising an attaching plate and a staple carried by said attaching plate, with one leg resilient, said staple consisting of a tongue of metal and an integral crosshead stamped from the attaching plate and formed into a loop and with the crosshead bridging the slot in the plate left by the tongue, said crosshead having its ends clinched on the underside thereof of the plate on either side of the slot thereby securing said crosshead against lifting from the plate and said plate being slotted to receive said clinched ends, and the crosshead being left with limited movement in the plane of the plate.
6. In a device of the type described, a latching staple having a leg rigidly mounted on said base and a leg movable relatively to the rigid leg and constructed with a recess, a hasp for said staple having a portion for engaging in said recess, and means for engaging said movable leg to move said leg out of engagement with said hasp.

7. In a device of the character described, the combination of a hasp and a staple having a notched movable leg, said hasp having a lever pivoted at one end adapted to engage the movable leg of said staple whereby manipulation of said lever moves said leg to release said hasp from said notched leg.

Signed at Chicago, Illinois, this 4th day of Nov., 1926.
